ULTRA HIGH FREQUENCY GENERATOR

Filed July 11, 1940

UNITED STATES PATENT OFFICE

2,568,325

ULTRA HIGH FREQUENCY GENERATOR

Hymen Diamond, Pittsburgh, Pa., assignor to
Westinghouse Electric Corporation, East Pitts-
burgh, Pa., a corporation of Pennsylvania

Application July 11, 1940, Serial No. 344,832

12 Claims. (Cl. 315—6)

1 My invention relates to ultra-high frequency apparatus and especially to apparatus incorporating hollow body resonators.

Recently, ultra-high frequency generators have been developed in which hollow body resonators are interposed in the path of the charges in a discharge device. In such resonators, the frequency is dependent on the dimensions of the resonators and can only be varied by changing the resonator dimensions. For proper operation of the generator, the resonators must be tuned and therefore their dimensions must be varied. Since the resonators are subjected to the discharge in a vacuum, difficulty has been experienced in tuning them.

It is one of the objects of my invention to provide a tuning means capable of accurate adjustment for the resonators of an ultra-high frequency generator.

Another object of my invention is to provide suitable tuning means for the resonators of an ultra-high frequency generator.

A general object of my invention is to provide a method for precisely tuning a hollow body resonator.

In accordance with the broad aspects of my invention, the resonant frequency of a hollow body resonator may be changed by varying its temperature. Specifically, my invention contemplates the external electrical control of a movable portion of the resonators. Preferably, a hollow body resonator is provided with a vane supported from a lever which changes its position under the influence of heat. The lever may be provided with an electrical heater, the temperature of which may be controlled externally.

Other aspects and advantages of the invention will be apparent from the following description and drawing in which:

Fig. 1 is a view partly in cross section and partly diagrammatic of a preferred embodiment of my invention, applied to an ultra-high frequency apparatus utilizing hollow body resonators.

Fig. 2 is a view on lines II—II of Fig. 1.

In Fig. 1, I have disclosed a particular type of ultra-high frequency apparatus utilizing hollow space resonators for which my tuning means is especially adapted, although my invention may be applied to other type of high-frequency apparatus.

The apparatus shown in the drawing comprises a cylindrical metallic container 1 of a suitable vacuum-tight material such as copper or steel. Since substantial heat is developed in the container and must necessarily be dissipated, it is

desirable that the container be provided with a cooling system. The container 1 is provided with a flange 2 which is secured to an end wall of the container. The flange 2 is provided with external cooling coils 3 through which a cooling medium such as water may be conducted.

An electron-emissive cathode assembly 5 is supported from an insulating ring 7 secured to an end wall of the container. The cathode assembly 5 comprises a heater 9 enclosed within an emissive cap 11, the outer surface of which is covered by a readily emissive material such as a combination of alkaline earth oxides. The cap 11 is flanged and the flanges 13 are supported on a dish-shaped disc 15 having a perforation 16 at its center through which the heater 9 extends.

A potential of the order of several thousand volts is impressed between the emissive cap 11 and ground from a suitable source 17 which may be of the usual commercial 60 cycle type. The container 1 is also grounded and the potential which is thus impressed between the container 10 wall and the cathode cooperates with the dish-shaped electrode 15 to convert the electrons emitted from the cap 11 into a narrow high velocity stream.

A conducting partition 19 with an openwork 21 at its center is secured to the cylindrical wall of the container 1 a short distance from the cathode 5. The partition is at ground potential, and it accelerates the electrons in the stream. The stream passes through the openwork 21 and then, after moving across a narrow gap 23, passes through another openwork 25 which forms one end of a hollow conducting cylinder 27. The cylinder 27 is supported from a second partition 29 which is centrally disposed in the container 1 and to which it is secured coaxial with the container 1. The supporting partition 29 is provided with a gap 31 adjacent one region of the wall of container 1, and a vane 33 supported from a rod 35 extends into the gap. The rod 35 supporting the vane is secured to a special adjusting and control means hereafter more fully described.

The cylinder 27 provides a field-free space through which the electron stream moves in an axial direction. The stream passes out of the cylinder through the remote end 39 which is also an openwork and then moves across another narrow gap 41. The openwork 43 of a third partition 45 is in the path of the stream at the end of the gap 41 and the stream passes through it and impinges on a deflecting electrode 47. The deflecting electrode 47 is suspended from a plurality of symmetrically disposed insulators 49 secured to the rear end of the container 1 so that its axis is coincident with the axis of the container. It is composed of a material that has a

secondary-emission ratio substantially smaller than 1. When the stream first impinges on the electrode 47, the electrode collects a charge and becomes electrically negative. The potential of the electrode is soon such as to oppose the forward motion of the electrons in the stream and the latter are, therefore, deflected to the container wall where they are dissipated.

In passing through the gaps 23 and 41 and the cylinder 27 the energy imparted to the stream by the source 17 is converted into high frequency radiant energy. The region bounded by the first partition 19, the openwork 25, the wall of the cylinder 27 between the central partition 29 and the openwork 25, the partition 29 and the wall of the container 1 between the partitions 19 and 29 including the portion of the vane 33 therein, 29 constitutes a hollow body resonator, one of the resonant frequencies is that which is radiated. The resonator is excited to oscillate at the selected frequency and as the electron stream passes through the gap 23 within the resonator, the electrons are influenced by the electric field corresponding to the excitation of the resonator. The electric vector of the field causes a periodic variation of longitudinal velocity at the frequency of the field. This variable velocity is superimposed on the average velocity corresponding to the D.-C. voltage applied between the cathode and the metallic body of the resonators. The electrons, therefore, move at different speeds as they pass into the field-free space within the cylinder 27. As the electrons move through the cylinder, they collect in groups at predetermined positions because the fast electrons tend to catch up with the slow ones.

The cylinder 27 is of such length that the electrons are bunched in groups when they pass through the openwork 39 into the adjacent gap 41. The gap 41 is a portion of the region of a hollow body resonator bounded by the partition 45, the adjacent openwork 39 of the cylinder 27, the wall of the cylinder 27 between the central partition 29 and the openwork 39, the central partition 29 and the wall of the container 1 between the partition 29 and the lower partition 45 including the portion of the vane 33 to the right of the central partition.

The last-mentioned resonator is preferably dimensioned the same as the resonator between the upper partition 19 and the central partition 29 so that one of its resonant frequencies is the same as the selected frequency of the latter. Slight differences in frequency may be compensated by regulating the control means 37, hereinafter described, to the extent that the vane 33 moves farther into the first or second resonator as indicated by the arrows.

The resonator including the gap 41 is thus excited to oscillate at the same frequency as the resonator containing the other gap 23. By proper choice of D.-C. voltage and length of cylinder 27 the groups of electrons are made to cross the gap 41 at the time, when the electric field at this gap 41 retards their motion. The electrons, therefore, give up a substantial fraction of their kinetic energy to the field and the energy is converted into radiant energy.

The energy is radiated by means of a suitable antenna which is fed through a transmission line 51 comprising a shielded elongated conductor 53 sealed through the container 1 having a loop 55 extending into the energy-generating resonator with the gap 41. The loop is oriented so that it is threaded by the magnetic vector

of the electromagnetic field within the resonator. The first resonator with the gap 23 whereby the velocity of the electron stream is modulated, is excited to oscillate by a loop 57 which extends between the two resonators through an opening 54 in the separator wall of the central partition 29. This is the usual feed-back connection where the apparatus is used primarily to produce oscillations. Where the apparatus is used for amplifying purposes, the modulating resonator with the gap 23 may be excited to oscillate by a proper source of high frequency oscillations.

The electron stream does not give up the total energy to the energy-generating resonator with the gap 41. After passing through the latter resonator, the stream is deflected by the insulated electrode 47 to the wall of the container 1 where the charge is dissipated.

In order to tune the two hollow resonators containing the gaps 23 and 41, I provide a copper plate 33 vertically extending through a slot 31 in the common partition 29 between the two hollow resonators. This plate or vane 33 is connected by 35 to a bimetallic strip 60 having its other end supported at 61 in an insulating casing 62 secured and sealed to the casing around the opening 63, through which the connecting rod 35 extends. The bimetal 61 is surrounded by a heating coil 64 connected to electrical heating means 65 controlled by rheostat 66. Whenever the tuning between the two hollow resonators is to be varied, the heating of the bimetal is regulated by the rheostat 66 to move the copper vane 33 up further into the first hollow resonator or down into the second hollow resonator, as desired. It is apparent that the bimetallic strip must be pre-set to place the vane 33 mainly in one resonator so that the application of heat will move it first to the position illustrated and then move it into the other resonator.

I have accordingly disclosed a tuning means for the hollow resonators which is especially suitable for a sealed-off casing and one that is both positive and accurate in making the variation desired in the tuning of the apparatus.

In addition to the elements included in the arrangement described herein the apparatus may incorporate any contrivances used generally in the cathode ray art in the same connection (such as improved processing devices) without departing from the scope of the invention.

The temperature of the bimetal 61 need not necessarily be controlled by an electric heater 64. The casing 62 may be immersed in a constant temperature bath and the temperature of the bath may be controlled as desired. Moreover, the whole generator may be immersed in a constant temperature bath and the temperature of the latter bath may be adjusted. Since large variations in temperature produce substantial variation in the dimensions of a hollow body, adjustments may be effected without the vane 33 by immersing the generator in a bath which may be varied between a very low temperature as, for example, that of liquid air or oxygen and a high temperature. The bimetal 61 may under certain conditions be replaced by a single element of high thermal expansivity.

Although I have shown and described a certain specific embodiment of my invention, I am fully aware that many modifications thereof are possible. My invention, therefore, is not to be restricted except in so far as is necessitated by the spirit of the appended claims.

I claim:

1. An ultra-high frequency device comprising a container, a plurality of electrodes therein defining a discharge path, a plurality of hollow body resonators in said discharge path, a metal part adapted to move into said hollow body resonators, and means for moving said metal part, said means including electrical conductors sealed through said container.

2. An ultra-high frequency device comprising a container, a plurality of electrodes therein defining a discharge path, a plurality of hollow resonators adjacent one another in said discharge path, a metal part adapted to move into either of said hollow body resonators, and means for moving said metal part, said means including electrical conductors sealed through said container.

3. An ultra-high frequency device comprising a container, a plurality of electrodes therein defining a discharge path, a plurality of hollow body resonators in said discharge path having a common partition, a metal part in an opening in said common partition adapted to move into either of said hollow body resonators, and means for moving said metal part, said means including electrical conductors sealed through said container.

4. An ultra-high frequency device comprising a container, a plurality of electrodes therein defining a discharge path, a plurality of hollow body resonators in said discharge path, a metal part adapted to move into said hollow body resonators, a bimetal supporting said metal part, and electrical heating means about said bimetal for controlling the movement of said metal part.

5. An ultra-high frequency device comprising a container, a plurality of electrodes therein defining a discharge path, a plurality of hollow body resonators adjacent one another in said discharge path, a metal part adapted to move into either of said hollow body resonators, a bimetal supporting said metal part, and electrical heating means about said bimetal for controlling the movement of said metal part.

6. An ultra-high frequency device comprising a container, a plurality of electrodes therein defining a discharge path, a plurality of hollow body resonators in said discharge path having a common partition, a plate of metal in an opening in said common partition adapted to move into either of said hollow body resonators, a bimetal supporting said plate and electrical heating means about said bimetal for controlling the movement of said plate.

7. An electric discharge device comprising an envelope, means for producing a stream of electrical charges in said envelope, a hollow-body resonator interposed in the path of said stream, a portion of said resonator being capable of change in position to vary the resonant frequency of said resonator, thermal means connected to said portion for changing the position of said portion to vary the resonant frequency of said resonator, and electrical conductors sealed through a part of said envelope for electrically controlling said thermal means.

8. An ultra-high frequency device comprising a container, a plurality of electrodes therein defining a discharge path, hollow-body resonator

means in said path, said resonator means including a portion movable relative to remainder of said resonator means, means actuatable in response to temperature changes for moving said portion relative to said remainder, and temperature varying means cooperative with said actuatable means for determining the position of said portion.

9. An electric discharge device comprising a hollow-body resonator, a cathode, and means for bunching electrons emitted from said cathode and causing the bunched electrons to give up energy in said resonator, in combination with mechanical means for altering the distributed capacity and inductance of said resonator and thermal means for actuating said mechanical means.

10. An electric discharge device comprising an evacuated envelope, said envelope providing a hollow-body resonator, a cathode in said envelope for directing electrons through said resonator, means for bunching electrons and causing the bunched electrons to give up energy in said resonator, mechanical means within the evacuated envelope and in part within said resonator for altering the distributed capacity and inductance of said resonator, and thermal means for actuating said mechanical means.

11. An electric discharge device comprising an evacuated envelope, said envelope providing a hollow-body resonator, a cathode in said envelope for directing electrons through said resonator, means for bunching electrons and causing the bunched electrons to give up energy in said resonator, mechanical means within the evacuated envelope and in part within said resonator for altering the distributed capacity and inductance of said resonator, and electrically heated thermal means for actuating said mechanical means.

12. An electric discharge device comprising an evacuated envelope, said envelope providing adjacent hollow-body resonators, a cathode in said envelope for directing electrons through said resonators and causing the bunched electrons to give up energy in one of said resonators, mechanical means partly in each resonator and movable with respect to each so that withdrawal thereof from one resonator introduces more of said means into the other resonator for equating the resonant frequency of the two resonators, and thermal means for moving said mechanical means.
